METHOD OF INDUCING ANALGESIA BY 4-(p-CHLOROPHENYL)-1,2,3,6-TETRAHYDRO-PYRIDINE

John H. Biel, Milwaukee, Wis., assignor to Lakeside Laboratories, Inc., Milwaukee, Wis., a corporation of Delaware
No Drawing. Filed Aug. 8, 1961, Ser. No. 129,951
6 Claims. (Cl. 167—65)

This invention relates to chemical compounds having medicinal activities. More particularly, this invention is concerned with the use of certain pyridine derivatives as medicinals in animals, as well as novel pharmaceutical compositions containing the pyridine compounds.

It has been found according to the present invention that 4-phenyl-1,2,3,6-tetrahydropyridines, and nontoxic pharmaceutically acceptable salts thereof, exert analgetic, spasmolytic and sedative activity in animals. These compounds have not yet been demonstrated clinically to be effective in humans.

The 4-phenyl-1,2,3,6-tetrahydropyridines which appear to exert such activity are the compounds of the formula

either as the free bases, or salts thereof, wherein R is hydrogen, a lower alkyl such as methyl, ethyl, propyl and isopropyl, an aralkyl group and particularly a phenyl-lower alkyl such as benzyl and phenethyl, a lower alkenyl such as allyl, a lower alkynyl such as propargyl, an amino substituted lower alkyl such as dimethylaminoethyl, and R₁ is hydrogen, or at least one substituent such as a halogen such as chlorine and bromine, a halo-lower alkyl such as chloromethyl and trifluoromethyl, nitro, a lower alkyl such as methyl and ethyl, a lower alkoxy such as methoxy and ethoxy, a carbo-lower alkoxy group such as carbo-methoxy and carbethoxy, or a lower alkylenedioxy such as 3,4-methylenedioxy.

Many compounds of the described group are reported in the J. Am. Chem. Soc., 72, 3134 (1950); 77, 5698 (1955), and 78, 1702 (1956).

Some of the specific compounds which can be used are:

4-phenyl-1,2,3,6-tetrahydropyridine,
4-phenyl-N-methyl-1,2,3,6-tetrahydropyridine,
4-phenyl-N-benzyl-1,2,3,6-tetrahydropyridine,
4-phenyl-N-phenethyl-1,2,3,6-tetrahydropyridine,
4-phenyl-N-(2-dimethylaminoethyl)-1,2,3,6-tetrahydropyridine,
4-(p-chlorophenyl)-1,2,3,6-tetrahydropyridine,
4-(p-trifluoromethylphenyl)-1,2,3,6-tetrahydropyridine,
4-(m-carbethoxyphenyl)-1,2,3,6-tetrahydropyridine,
4-(3,4-methylenedioxyphenyl)-1,2,3,6-tetrahydropyridine,
4-(p-chlorophenyl)-N-allyl-1,2,3,6-tetrahydropyridine and
4-(p-methylphenyl)-N-propargyl-1,2,3,6-tetrahydropyridine.

Such compounds can be employed as the base or as nontoxic pharmaceutically acceptable acid addition salts including the hydrochloride, sulfate, phosphate, maleate, fumarate and citrate, as well as salts formed with aromatic carboxylic acids containing an ortho phenolic hydroxy group, such as salicylic acid.

Although one or more of the 4-phenyl-1,2,3,6-tetrahydropyridines can be administered as the pure compounds to animals, it is advisable, however, to first combine one or more of the compounds with a suitable phar-

2

maceutical carrier to attain a more satisfactory size to dosage relationship.

Pharmaceutical carriers which are liquid or solid can be used. The preferred liquid carrier is water. Flavoring materials may be included in the solutions as desired.

Solid pharmaceutical carriers such as starch, sugar, talc and the like may be used to form powders. The powders may be used as such for direct administration, or, instead, the powders may be added to suitable foods and liquids, including water, to facilitate administration.

The powders also may be used to make tablets, or to fill gelatin capsules. Suitable lubricants like magnesium stearate, binders such as gelatin, and disintegrating agents like sodium carbonate in combination with citric acid may be used to form the tablets.

Unit dosage forms such as tablets, capsules and suppositories may contain any suitable predetermined amount of one or more of the compounds as the base, or in the form of a nontoxic salt, and may be administered one or more at a time at spaced intervals. Such unit dosages can contain, illustratively, from about 5 to 500 mgm., and advisably 15 to 100 mgm., of an active compound. Variation in activity between compounds is to be expected. Such variations are to be taken into account in utilizing these compounds. Such determinations are readily made by those skilled in the art. Daily dosages of about 0.01 to 6.0 gm. are suitable. The oral route of administration is preferred.

Representative of the analgetic activity of these compounds is that of 4-(p-chlorophenyl)-1,2,3,6-tetrahydropyridine. Its analgetic activity was determined using the tail clamp procedure described in the British Journal of Pharmacology, 9, 280 (1954). This method employs the application of a painful stimulus to the root of an animal's tail and uses the time required for the animal to react to the stimulus as a measure of analgetic activity. The analgetic value is the dose required to give a 100 percent increase in reaction time and is measured in mg./kg. Using this method, 4-(p-chlorophenyl)-1,2,3,6-tetrahydropyridine HCl was active at 5.3 mg./kg. (oral, mice) while codeine was active at 14.0 mg./kg. (oral, mice) and Analexin [2-(beta-hydroxyphenethylamino)-pyridine] at 115.0 mg./kg. (oral, mice).

A typical tablet can have the composition:

	Mg.
4-phenyl-1,2,3,6-tetrahydropyridine HCl	30
Starch U.S.P.	57
Lactose U.S.P.	73
Talc U.S.P.	9
50 Stearic acid	6

The salicylate salts of the 4-phenyl-1,2,3,6-tetrahydropyridine compounds are considered novel and are believed, in general, to possess more pronounced analgesia than the bases or other salts.

The following example illustrates the preparation of the salicylate salts.

EXAMPLE

4-(p-Chlorophenyl)-1,2,3,6-Tetrahydropyridine Salicylate

60 A 10 gm. sample (0.044 mole) of 4-(p-chlorophenyl)-1,2,3,6-tetrahydropyridine hydrochloride was dissolved in water, made alkaline with potassium carbonate and the solid base collected by filtration and dried in vacuo. The base was dissolved in 300 ml. of warm isopropyl alcohol and filtered into a solution of 6.07 gm. (0.044 mole) of salicylic acid in 50 ml. of ethyl ether. Precipitation occurs immediately. The solids were filtered under anhydrous conditions, washed well with ether and oven dried, yielding 12.5 gm. (85.7 percent), M.P. 231-233° C. (d).

70 *Analysis.*—Calcd. for C₁₈H₁₈ClNO₃: N, 4.22; N.E. 331.8. Found: N, 4.40; N.E. 314.16.

A 2 gram sample was recrystallized from a hot mixture

of 100 ml. of acetonitrile and 15 ml. of ethanol, M.P. 231-233° C.

Various changes and modifications of the invention can be made and, to the extent that such variations incorporate the spirit of this invention, they are intended to be included within the scope of the appended claims.

What is claimed is:

1. A therapeutic composition in dosage unit form comprising a pharmaceutical carrier and from 5 to 500 mgm. of 4-(p-chlorophenyl)-1,2,3,6-tetrahydropyridine.

2. A therapeutic composition in dosage unit form comprising a pharmaceutical carrier and from 5 to 500 mgm. of 4-(p-chlorophenyl)-1,2,3,6-tetrahydropyridine salicylate.

3. A therapeutic composition in dosage unit form comprising a pharmaceutical carrier and from 5 to 500 mgm. of 4-(p-chlorophenyl)-1,2,3,6-tetrahydropyridine hydrochloride.

4. The method of inducing analgesia in an animal which comprises administering to the animal a safe but

effective amount of 4-(p-chlorophenyl)-1,2,3,6-tetrahydropyridine.

5. The method of inducing analgesia in an animal which comprises administering to the animal a safe but effective amount of 4-(p-chlorophenyl)-1,2,3,6-tetrahydropyridine salicylate.

6. The method of inducing analgesia in an animal which comprises administering to the animal a safe but effective amount of 4-(p-chlorophenyl)-1,2,3,6-tetrahydropyridine hydrochloride.
